DESIGN FOR A PHOTOMETER

Alfred William Hubbard, Stillwater, Minn., assignor of one-third to Joseph C. N. Rowell, and one-third to Theodore H. Rowell, both of Baudette, Minn.

Application June 24, 1940, Serial No. 93,202

Term of patent 14 years

To all whom it may concern:

Be it known that I, Alfred William Hubbard, a citizen of the United States and residing in the city of Stillwater, county of Washington, and State of Minnesota, have invented a new, original, and ornamental Design for Photometer, of which the following is a specification, reference being had to the accompanying drawing, forming a part thereof, wherein

Fig. 1 is an elevation of one side of a photometer embodying my design;

Fig. 2 is a plan view thereof;
Fig. 3 is an elevation of the side opposite to that illustrated in Fig. 1; and
Fig. 4 is a front elevation.

I claim:
The ornamental design for a photometer, as shown.

ALFRED WILLIAM HUBBARD.
